CAR CONSTRUCTION

Filed Oct. 7, 1929

By Joseph Harris
his Atty.

UNITED STATES PATENT OFFICE

WILLIAM A. GEIGER, OF CHICAGO, ILLINOIS, ASSIGNOR TO W. H. MINER, INC., OF CHICAGO, ILLINOIS, A CORPORATION OF DELAWARE

CAR CONSTRUCTION

Application filed October 7, 1929. Serial No. 397,796.

This invention relates to improvements in car construction.

One object of the invention is to provide a car construction including the usual coupler means at each end of the car, and a draft sill structure with respect to which the car body is yieldingly movable in a lengthwise direction, wherein the draft sill structure includes draft sill means connected to each coupler and means connecting the draft sill means of one coupler to that of the other coupler, comprising a yoke-acting means fixed to each draft sill member and a shock absorbing device within the yoke means and co-acting therewith to yieldingly oppose relative separation in a lengthwise direction of the two draft sill means, to cushion draft shocks, and wherein relative approach of the two draft sill means is also cushioned by said shock absorbing mechanism, the latter being compressed between stop means fixed to the sill means.

A further object of the invention is to provide a car construction of the character indicated in the preceding paragraph, wherein the connecting means for the relatively movable sill means and the fixed stop-acting means on the same is so designed that any well known type of spring or friction shock absorbing means may be employed, to oppose relative movement of said sill means, without alteration or change of said shock absorbing means.

Other objects of the invention will more clearly appear from the description and claims hereinafter following.

In the drawing forming a part of this specification, Figures 1 and 2 are horizontal longitudinal sectional views through the underframe structure of a railway car, illustrating my improvements in connection therewith, Figure 1 showing the construction at one end of the car and Figure 2 being a continuation of Figure 1 and showing the construction at the central portion of the car. Figure 3 is a longitudinal vertical sectional view, corresponding substantially to the line 3—3 of Figure 2. Figure 4 is a transverse vertical sectional view, corresponding substantially to the line 4—4 of Figure 3. And

Figures 5 and 6 are detail perspective views of a sectional yoke member, and illustrate a different embodiment of the invention, the parts of the yoke member being shown separated in these two views.

Referring first to the embodiment of the invention illustrated in Figures 1 to 4, inclusive, 10—10 indicates channel-shaped movable draft sills of a railway car structure. As shown in Figures 1 and 2, the sills are arranged in pairs at opposite ends of the car, each pair being spaced the standard distance apart. Figure 1 shows the pair of sills at one end of the car while Figure 2 illustrates, in addition to this pair of sills, the inner end portions of the pair of sills at the other end of the car. Inasmuch as the arrangement of each pair of sills is identical, those at one end of the car, only, are fully and completely illustrated in the drawing. Each pair of sills has coupler means connected to the outer ends thereof. As shown in Figure 1, the coupler means at the lefthand end of the car is indicated by 11, the same being connected to the sills 10 by means of a transverse coupler key 12 extending through an opening in the coupler shank and alined openings or slots 13—13 provided at the outer ends of the sills.

The slots of the sills are reinforced by a casting 14 disposed between the sills, which casting also forms a spacing and bracing member for the sills. The casting 14 may be secured to the vertical webs of the sills in any suitable manner and, as herein shown, is riveted thereto. The casting 14 is provided with a pocket 15 at the inner end portion thereof, which contains a shock absorbing spring 16 cooperating with the coupler, to yieldingly oppose inward movement thereof. The spring 16 has front and rear follower members or discs 17—17 cooperating therewith, the same being connected by a retainer bolt 18. A follower plate 19 is preferably interposed between the outer follower 17 and the butt end of the coupler shank. As clearly shown in Figure 1, a certain amount of clearance is provided between the key 12 and the inner end walls of the slots 13 of the sills and also between the front edge of the key and the front end wall of the opening in the cou-

pler shank, so that a limited amount of inward movement of the coupler with respect to the sills 10 is permitted, to effect compression of the spring 16 in buff. At the outer ends, the sills 10 are also preferably provided with a striking casting 20 which may be secured thereto in any suitable manner, the striking casting being provided with a carry iron section 21, which supports and guides the coupler shank. One of the body bolsters of the car is indicated by 22, in Figure 1, it being understood that a similar body bolster is provided at the other end of the car. A combined stop and filler casting 23 is secured to the body bolster, the casting having the side wall thereof spaced from the adjacent portions of the bolster 22 so as to provide longitudinal guideways for the pair of sills 10. Approximately at the bolster 22 each member of the pair of sills is provided with a stop casting 24, which cooperates with an outer follower plate 25. Spaced inwardly from the stop lug castings 24 is a pair of additional stop lug castings 26-26 which are fixed to the respective sills of the car. The stop lugs 26 cooperate with an inner follower plate 27. In order to brace the sills 10 and hold the same properly spaced, a connecting plate 28 is provided near the stop lugs 26, the plate having its opposite ends secured to the bottom flanges of the sills 10. The followers 25 and 27 cooperate with shock absorbing means in the form of two coil springs 29-29 interposed between said followers. In order to limit rearward or inward movement of the follower 25, a pair of stop bars 30-30 is provided, the same being anchored at their outer ends to the filler casting 23 by means of vertical pins 31-31 extending through enlargements at the front ends of the bars 30 and through suitable openings provided in the casting 23. The bars 30 extend through openings provided in the followers 25 and 27 and have retaining means in the form of cotter pin members 32-32 extending therethrough. As will be evident, the follower 27, by engagement with the cotter pins 32, will be held against rearward or inward movement.

As clearly illustrated in Figure 2, each pair of sills 10 is provided with a pair of stop lug castings 33-33 adjacent the inner end thereof, the castings being spaced a predetermined distance from the extremities of the sills, as illustrated. Each pair of sills also has a yoke member 34 secured thereto. As shown, each yoke member comprises top and bottom arms 35-35 and a connecting vertical end portion 36, each yoke member being thus of substantially U-shaped form. The arms 35 at the inner ends are widened so as to form plate-like sections which are of such a width as to overlap the corresponding pair of sills 10. As most clearly illustrated in Figure 2, the top and bottom plate-like sections of the

arms are secured to the top and bottom flanges of the corresponding pair of sills 10.

Referring to Figures 3 and 4, it is pointed out that the U-shaped yoke member 34 connected to one of the sills is of lesser height than the other yoke member and the two members are telescoped relatively to each other. The outer arm portions of each yoke member are of such a width that they pass freely between the stop lug castings 33 of the adjacent pair of sills 10.

The plate-like sections of the arms of the inner yoke member are cut away as indicated at 41-41 to accommodate the vertical end section 36 of the other yoke and allow relative longitudinal movement of the two yoke members to such an extent as to permit full compression of the shock absorbing means with which the yoke members cooperate.

In order to oppose relative separation of the two pairs of sills 10-10 and 10-10 in a direction lengthwise of the car, a cushioning or shock absorbing means is disposed within the yoke members 36. This shock absorbing means may be of either the spring or friction type and of any well known design. In the present case, a friction shock absorbing means 37 is illustrated, the same comprising the usual friction shell, cooperating friction shoes, and wedge member 38. It will be understood that the friction shell contains the usual spring resistance which opposes inward movement of the friction shoes and wedge member. The friction shell has the closed end thereof bearing on the stop lug castings 33 of the pair of sills 10 shown at the righthand side of Figure 2 and a follower plate 39 is interposed between the wedge block 38 and the stop lug castings 33 of the other pair of sills 10.

Figures 1 to 4, inclusive, illustrate the normal position of the parts, with the inner ends of the two pairs of sills 10 spaced apart so as to permit relative approach of the same, when a buffing force is applied to either of the couplers of the car.

The operation of my improved construction, when a pulling or draft action is applied to the coupler at one end of the car, is as follows: The sills 10-10 at one end of the car will be pulled outwardly in unison with the corresponding coupler, through the medium of the connecting key 12, thereby also causing an outward movement of the follower 27, which is engaged by the stop casting 26. During the outward movement of the follower 27, the spring resistance members 29-29 will be compressed against the follower 25, which remains stationary, due to engagement thereof with the stop casting 23. While the sills 10 at one end of the car are pulled outwardly, the corresponding yoke member 34 will be moved in the same direction, thereby compressing the shock absorbing mechanism 37 between the vertical end

member of this yoke and the vertical end member of the yoke secured to the other pair of sills 10. During this action, there will also be a tendency for the sills at the other end of the car to move, the same being yieldingly opposed by springs at that end of the car corresponding to the springs 29 shown in Figure 1. As will be evident, relative movement of each pair of sills 10 with respect to the car body is thus yieldingly opposed during a draft action and relative separation of the two pairs of sills 10, in a lengthwise direction, is also yieldingly resisted to oppose draft shocks.

Upon a buffing action being applied to the coupler 11 at the lefthand end of the car, as shown in Figure 1, the spring 16 will first be compressed, until the clearance between the front end wall of the opening in the coupler shank and the coupler key 12 and the clearance between this key and the rear end walls of the slots 13 of the sills 10 is taken up, whereupon the sills 10 will be forced to move rearwardly or inwardly, in unison with the coupler. While the sills 10 are being moved inwardly, the follower 25 will be forced rearwardly by the stop lug castings 24—24, thereby compressing the springs 29 against the follower 27, which is held stationary by the anchoring stop rods 30—30. Movement of the sills 10 with reference to the car body is thus yieldingly opposed. During the described inward or rearward movement of the sills 10 at the lefthand end of the car, the stop lug castings 33 adjacent the inner ends of these sills will force the follower 39 to the right, as seen in Figure 2, thereby compressing the friction shock absorbing mechanism 37 against the stop lug castings 33 of the other pair of sills 10. During this action, there will be a tendency of the sills 10—10 at the righthand end of the car, as seen in Figure 2, to move lengthwise of the car. This movement is resisted by the spring shock absorbing means at the righthand end of the car, corresponding to the springs 29 shown in Figure 1. Relative approach of the two pairs of sills lengthwise of the car will be positively limited by engagement of the inner ends of the sills of the two pairs. The clearance between the inner ends of the two pairs of sills is preferably made the same as the clearance between the follower 39 and the corresponding end of the friction shell of the friction shock absorbing mechanism, so that the follower will engage the shell at the same time that movement of the sills is limited.

Referring next to the embodiment of the invention shown in Figures 5 and 6, it is pointed out that the yoke construction illustrated in said figures is employed in connection with two pairs of movable sills and shock absorbing devices of the same character as illustrated in Figures 1 to 4, inclusive. Two

yoke members of the type shown in Figures 5 and 6 are employed in connection with my improvements, the yokes being secured respectively to the inner ends of the two pairs of sills, as will be understood. Each yoke member comprises top and bottom arms 135—135, the top arm being provided with a right angular extension 137, which forms the vertical end member of the yoke. As shown, the vertical end member 137 is reduced in width at the bottom end thereof, as indicated at 138, thereby providing a tongue adapted to fit within an opening 139, provided at the outer end of the bottom arm 135 of the yoke. The tongue 138 is of such a length that it projects through and beyond the bottom arm 135. In order to prevent separation of the top and bottom arms 135 of the yoke, a cotter pin or any other type of securing means may be employed, the same extending through an opening 140 at the outer end of the tongue 138. The top and bottom arms 135—135 of the yoke are provided with relatively wide plate-like sections at the inner ends thereof which correspond to the plate-like sections of the yoke members 34 hereinbefore described, and are secured to the top and bottom flanges of the movable sills. The upper arm of the yoke may be either riveted or bolted in place and the lower arm will be bolted so as to permit insertion or removal of the gear. As will be understood, the two yoke members which cooperate with the two pairs of sills are of different heights, so that they may be telescoped. The plate-like sections of the arms of the yokes are cut out as indicated at 141—141, to accommodate the vertical end section 137 of the other yoke and allow the necessary amount of relative movement of the two yoke members during compression of the shock absorbing mechanism.

By providing the separable yoke construction illustrated in Figures 5 and 6, the bottom arm of the yoke member may be detached so that the shock absorbing mechanism may be readily removed from between the yoke members, for the purpose of repair or replacement.

I have herein shown and described what I now consider the preferred manner of carrying out my invention, but the same is illustrative, only, and I contemplate all changes and modifications that come within the scope of the claims appended hereto.

I claim:

1. In car construction, the combination with coupler means at opposite ends of the car; of a pair of spaced draft sills connected to each coupler, said sills being movable lengthwise of the car body; means yieldingly opposing relative movement of the sill members and car body; a U-shaped yoke member connected to each pair of sills, the arms at the open end of said yoke member being fixed to said sills and the closed end portion of

said yoke extending beyond said pair of sills and between the other pair of sills; and a shock absorbing means enclosed by said yoke members and adapted to be compressed between the closed ends thereof.

5 2. In car construction, the combination with coupler means at each end of the car; of a pair of spaced draft sills connected to each coupler means, each pair of sills being movable lengthwise of the car body; means yieldingly opposing relative movement of each pair of sills with respect to the car body; a yoke member connected to the inner ends of each pair of sills, each yoke member having 10 top and bottom arms, said yoke members being open at one end and having a connecting end section at the other end, the arms of each yoke member having plate-like enlarged sections at the open end of the yoke spanning 15 the corresponding pair of draft sills and secured respectively to the top and bottom thereof, said yoke members being telescoped; and a shock absorbing mechanism enclosed by 20 said yoke members.

25 3. In car construction, the combination with coupler means at each end of the car; of a pair of spaced sills connected to each coupler means, each pair of sills being movable lengthwise of the car; means yieldingly 30 opposing relative movement of the car body and sills; a yoke member connected to each pair of sills, each yoke member including top and bottom arms and a connecting end section; a shock absorbing means enclosed within 35 in said yoke members, each of said yoke members including a separable section detachably connected to the corresponding pair of draft sills, said section being detachable to permit removal and insertion of the shock absorbing 40 means.

In witness that I claim the foregoing I have hereunto subscribed my name this 5th day of October 1929.

45 WILLIAM A. GEIGER.
